(57) **CLAIM**

The ornamental design for a cooler within overalls, as shown and described.

DESCRIPTION

FIG. 1 is a front elevation view of a cooler within overalls, shown with detail enlarged and in the closed position; FIG. 2 is another front elevation view thereof, shown in the open position;

FIG. 3 is a right side elevation view thereof, shown in the open position;

FIG. 4 is a left side elevation view thereof, shown in the open position;

FIG. 5 is a third front elevation view thereof, shown with detail enlarged and in the open position; and,

FIG. 6 is a fourth front elevation view thereof, shown with detail enlarged, open, and in use.

The broken lines shown in the drawings depict portions of the cooler within overalls that forms no part of the claimed design. The broken lines showing the humanoid figure and shoes in the drawings depict environment that forms no part of the claimed design. For clarity, the dashed lines that appear internal to the solid lines depicting portions of the cooler within overalls are meant to indicate stitching and hereby are claimed as part of the design.
